UNITED STATES PATENT OFFICE.

ROBERT T. CARR, OF DETROIT, MICHIGAN.

DESIGN FOR A ROCKER-BODY.

No. 37,664.

Specification for Design.

Patented Nov. 14, 1905.

Application filed July 3, 1905. Serial No. 268,286. Term of patent 7 years.

To all whom it may concern:

Be it known that I, ROBERT T. CARR, a citizen of the United States, residing at Detroit, county of Wayne, State of Michigan, have invented a certain new, original, and ornamental Design for a Rocker-Body, of which the following is a specification, reference being had to the accompanying drawing, which forms a part of this specification.

The figure is a side elevation of a rocker-body, showing my new design.

I claim—

The ornamental design for a rocker-body, as shown.

ROBERT T. CARR.
